CLAIM

The ornamental design for a display rack with light as shown and described.

DESCRIPTION

FIG. 1 is a rear perspective view of a display rack with light embodying my new design;

FIG. 2 is a front perspective view thereof;

FIG. 3 is a top plan view thereof, the bottom plan view being a mirror image thereof;

FIG. 4 is a front elevation view thereof; and,

FIG. 5 is a left elevation view thereof; the right elevation view being a mirror image thereof.

The dash-dash broken lines shown in FIGS. 1, 2, 4, and 5 illustrate portions of the display rack with light that form no part of the claimed design.

The claimed design is shown with a symbolic break represented by dot-dot broken lines in its length/height. The appearance of any portion of the display rack with light between the dot-dot broken lines forms no part of the claim.
